UNITED STATES PATENT OFFICE.

LEE P. HYNES, OF ALBANY, NEW YORK, ASSIGNOR TO CONSOLIDATED CAE-HEATING COMPANY, OF ALBANY, NEW YORK, A CORPORATION OF WEST VIRGINIA.

ELECTRIC HEATER.

Application filed February 10, 1922. Serial No. 535,534.

To all whom it may concern:

Be it known that I, LEE P. HYNES, a citizen of the United States, residing at Albany, in the county of Albany and State of New York, have invented certain new and useful Improvements in Electric Heaters, the following being a full, clear, and exact disclosure of the one form of my invention which I at present deem preferable.

For a detailed description of the present form of my invention, reference may be had to the following specification and to the accompanying drawings forming a part thereof, wherein—

Fig. 1 shows my invention in elementary form;

Figs. 2 and 3 show it arranged in a way particularly suitable for air heating;

Figs. 4 and 5 show its application for tank heating;

Figs. 6, 7 and 8 are modifications.

My electric heater is of the type recently devised by me wherein a tube or duct of refractory insulating material is formed on or placed in a body of metal or other substance to be heated, and a separable heating coil, preferably of a standard capacity with terminals permanently attached to include between them a predetermined length of wire, is subsequently threaded through the tube and its ends connected electrically to binding blocks set in a pocket or recess at the end of the tube. The present application relates to the form and application of the sheet-metal shell wherein one or more of the aforesaid refractory tubes are enclosed. In a prior application, Serial No. 508,542, filed October 18th, 1921, I have shown such a shell as formed from a malleable metal tube which is pressed into a tube of smaller diameter with radiating ribs thereon, except at the ends where it is left off of the original diameter but with a screw thread rolled therein for the reception of an insulating bushing. The binding blocks for the external-circuit connections are in a recess in the said bushing. I now purpose to construct an enclosing metal shell for the said refractory tube in separate parts, also to extend the sheet which constitutes one of the parts so as to receive one or more additional tubes therein or so as to become the wall of a vessel, container, or compartment wherein is the air, gas, liquid or other substance to be heated.

Referring to the drawings, Fig. 1 shows a sheet of metal A with a longitudinal semi-circular channel, *a*, with widened ends pressed or indented in it, and B is a similar sheet having a corresponding semi-circular channel *b*. These two sheets are placed together face to face with the two channels in alignment to form a metal tube for containing the refractory tube 4. The widened ends of the metal tube will receive the insulating plug or bushing of my aforesaid device which is shown in Fig. 5 at 9, the plug being suitably shaped to fit the widened end. The two sheets will be secured together by any suitable means, as by welding, or by rivets and the rivets may be supplanted or replaced by folding over the edges of sheet A upon sheet B. As shown in Fig. 5, a separable heating coil 5 will be threaded through the refractory tube 4 and its terminal 16 will be connected by a rod 6 of reduced heat-conducting capacity, to a binding block 8 which is set into the insulating plug or bushing 9 at the bottom of a recess therein. Instead of the separate refractory tube 4, I may enamel the inside of each channel, as shown in Fig. 8. When the sheets A and B are secured together there results, in effect, a two-part refractory tube fitted inside of the tubular portion of the metal shell. The enameling can be done to better advantage with the two-part shell than with an integral shell since the enamel can be more easily applied and inspected.

Instead of indenting a half-tube in each of the sheets A and B, one of them may be left flat, as shown in Fig. 6, and the other bent to enclose the refractory tube. In that case the refractory tube may be made flat on one side, as shown in Fig. 6, or it may be sealed in with a heat-insulating cement 10, as shown in Fig. 7. In Fig. 7 the sheet B is rolled with a series of radiating ribs, and the heat-insulating cement is extended in a layer between the sheets A and B, for which purpose an asbestos sheet may be used together with the cement, or any other suitable heat-insulating material employed.

In Figs. 2 and 3 the sheet A is extended to include a series of two or more refractory ducts, and the sheet is then secured at its edges to a suitable support D but spaced therefrom to permit of a circulation on both sides of the sheet of the air or other fluid to be heated. In Fig. 3 the refractory

tubes run vertically while the sheet A is left flat as in Fig. 6. This will permit a gravity-circulation of the fluid through the space between sheet A and support D. In Figs. 4 and 5 the sheet A is enlarged or extended to form the wall of a tank, in which a liquid, or other desired substance, may be heated. For this purpose the aforesaid channels may be indented in the tank wall, on the side thereof as shown in Fig. 4, or on the bottom as shown in Fig. 5. Over each indentation is placed a similarly indented plate B. Obviously the plate A may be left flat and only the plate B indented as in Fig. 6. One feature of importance is that the electrical connections with the heating coil are made outside of the tank. For example, as appears in Fig. 4, the refractory tube 4 may be shortened, whereby a space at the end of the metal tube will be left to form a recess in which is seated an insulating plate 11, whereon is secured a binding plate or block 12 for receiving the wire of the external circuit. A rod 6 of reduced heat-conducting capacity secured to one end of the coil has an eye at its outer end through which is passed a screw connecting it with the binding-plate 12. The end of sheet B which covers this recess is made detachable with an opening through it for the entrance of the external-circuit wire.

In Fig. 5 I have also shown the wall-heaters of Figs. 4 and 5 as supplemented by heaters of my original flattened-tube form extending across the inside of the tank from side to side and also arranged for external connection thereto of the circuit wires. For supporting the end of the heater a cupped disc A¹ with a central screw-threaded hub 40 is fastened on the inside of the tank wall, the joint being made tight by a packing gasket if desired. The screw-threaded end of the heater-shell fits into the hub of the disc. Thus the exposed end of the heater 45 is accessible through an opening in the wall of the tank through which it may project. The end of the heater-shell contains an insulating plug or bushing, 9, and at the bottom of a central recess therein is an inserted metal binding-block 8 to which the aforesaid rod 6 is connected. The outside of the tank may be covered with heat-insulating material 10 as shown on the bottom of the tank in Fig. 5, suitable openings therein being left for the circuit wires.

What I claim as new and desire to secure by Letters Patent is:

1. An electric heater comprising a metal shell made in separable parts suitably secured together, a refractory insulating duct fitted into the shell, and a heating coil extending loosely through the said duct.
2. An electric heater comprising a metal shell divided longitudinally into separable parts suitably secured together, a refractory

insulating duct fitted into the shell, and a heating coil extending through the said duct.

3. An electric heater comprising a metal shell made in parallel parts suitably secured together wherein an indented channel is formed, a refractory insulating duct in said channel and a heating coil contained in said duct.

4. An electric heater comprising a metal shell made in parallel parts suitably secured together one being folded over the other at the edge, a refractory insulating duct in said shell and a heating coil contained in said duct.

5. An electric heater comprising a metal shell with radiating ribs and split longitudinally along the ribs, fastening means on the ribs for securing the parts together, a refractory insulating duct in said shell and a heating coil in said duct.

6. An electric heater comprising a metal shell formed in parts suitably secured together and having a channel indented therein, a refractory insulating duct in said channel but shorter than the channel, a heating coil in said duct, and an insulated binding terminal in the said channel beyond the duct.

7. An electric heater comprising a metal shell formed in parts suitably secured together and having a channel therein leading into an enlarged recess at its end, a refractory insulating duct in said channel, and an insulated binding terminal in said recess.

8. An electric heater comprising two flat sheets face to face with a tubular passage between them formed by indenting one or both sheets and suitably secured together, a refractory insulating duct inclosed in said passage and a heating coil contained in said duct.

9. An electric heater shell of tubular form with longitudinal radiating ribs, said shell being composed of two flat sheets, one or both of which has indented in it a channel parallel to the ribs, and means for securing the two sheets together face to face.

10. An electric heater-shell comprising sheets of unequal width one or both of which are indented to form a tubular channel suitable to receive a tube of refractory insulation, and means for securing the two sheets together face to face.

11. An electric heater comprising an extended metal sheet with two or more tubular channels formed therein, a refractory insulating tube in each channel, and a heating coil in each tube.

12. An electric heater comprising an extended metal sheet with two or more tubular channels therein each channel being split longitudinally, a refractory insulating tube in each channel and a heating coil in each tube.

13. An electric heater comprising a split metal shell formed of sheets one of which

has a removable section, a refractory insulating tube in said shell and a heating coil in the said tube.

14. An electric heater comprising a split tubular shell of metal the interior of which is enamelled to form a refractory insulating tube fitted in the shell and a heating coil in said tube.

15. An electric heater comprising a split shell of sheet metal indented to form a tubular channel and enamelled along the inside of the channel to form therein a refractory insulating tube when the sheets are secured together, and a heating coil in the said tube.

16. An electric heater comprising a tubular metal shell, a refractory insulating tube therein split longitudinally, and a heating coil in said tube.

17. An electric heater comprising a tubular metal shell with ribs therein extended to form the wall of a container, a refractory insulating tube in each metal tube and a heating coil in said insulating tube.

18. An electric heater comprising a metal shell constituting the wall of a container with a series of tubular channels therein, a refractory insulating tube in each of said channels, and a heating coil in each insulating tube.

19. An electric heater comprising a metal

shell constituting the wall of a container with one or more tubular channels formed therein with an end recess or chamber accessible from outside the container, a refractory insulating tube in each channel and a separable heating coil in each tube with its terminal in said recess or chamber.

20. An electric heater comprising a metal shell constituting the wall of a container with one or more tubular channels formed therein, a refractory insulating tube in each channel, a heating coil in each tube, and a heat-insulating covering on one side of said shell.

21. An electric heater comprising a sheet-metal container-wall having one or more channels indented therein, a refractory insulating tube in each channel and a separable heater coil inserted in each tube.

22. An electric heater comprising a sheet-metal tube with extensions therefrom forming the wall of a container, a refractory insulating tube in said metal tube and a heating coil in said insulating tube with terminals accessible from outside the container.

Signed at Albany, county of Albany and State of New York, this 31st day of January, 1922.

LEE P. HYNES.
